UNITED STATES PATENT OFFICE.

JAMES HUBER, OF PHILADELPHIA, PENNSYLVANIA, ASSIGNOR TO VICKERS LIMITED,
OF WESTMINSTER, ENGLAND.

SUBMARINE MINE.

1,314,655.

Specification of Letters Patent.

Patented Sept. 2, 1919.

Application filed July 2, 1917. Serial No. 178,065.

To all whom it may concern:

Be it known that I, JAMES HUBER, a citizen of Switzerland, and residing at Philadelphia, in the county of Philadelphia and 5 the State of Pennsylvania, have invented certain new and useful Improvements in Submarine Mines; and I do hereby declare the following to be a full, clear, and exact 10 description of the invention, such as will enable others skilled in the art to which it appertains to make and use the same.

This invention relates to a submarine mine, and has for its primary object the provision of a mine wherein the sounding 15 ball will be released from the anchor prior to the release of the anchor from the mine itself.

The further object of the invention resides in so constructing the device, that the 20 means controlling the release of the anchor from the mine also controls the release of the sounding ball from the anchor.

Figure 1 is a fragmental elevation of a mine with a portion of the anchor broken 25 away and with my invention applied thereto.

Fig. 2 is a horizontal sectional view on line 2—2 on Fig. 1.

Fig. 3 is a vertical sectional view of the 30 means for securing the anchor to the mine.

Fig. 4 is a horizontal sectional view on line 4—4 on Fig. 3.

Fig. 5 is a view similar to Fig. 1, but showing a modified form of the invention.

Fig. 6 is a sectional view of a modified 35 form of sounding ball.

Fig. 7 is a top plan of the same with the cover removed.

Referring to Figs. 1 to 4, inclusive, I 40 have illustrated an anchor 1 and a mine 2 of the usual form, with which anchor the usual sounding ball 3 is associated.

The mine is secured to the anchor during the launching and until it reaches a predetermined depth by means similar to that described in my co-pending application, Serial 45 No. 173,182, filed June 6, 1917. This means includes a cylinder 4, which is pivotally mounted at 5, on an extension 6, of a plate 7. This plate 7, is secured to the side of the anchor 1 in any desired manner and is provided 50 with keepers or guides 8 for the purpose which will later appear. A tubular socket member 9 is screwed into the upper end of the cylinder 8, or is otherwise secured thereto, which member acts to close the end of the 55 cylinder. A piston 10 is operable in the cylinder 4 and is provided with a rod 11, which extends upwardly through the bottom of the socket 9 and into the same. This rod 11 is provided with a reduced portion 12 and 60 with a head 13, which head is provided with a cam face 14. A connecting element is adapted to extend into the tubular socket 9 and is of inverted U form having dependent legs 15 on the lower ends of which are 65 toe portions 16, which toe portions are adapted to engage within the reduced portion 12 of the head 11. This connecting element is adapted to be secured to the turnbuckle 17 of the attaching member which 70 passes over the mine. A retaining pin 18 passes through the two apertures in the tubular socket 9, and through corresponding apertures in the legs 15 of the connecting member. This pin may be of any desirable 75 form and material, such for instance as described in connection with the above mentioned co-pending application. The inside diameter of the tubular member 9 is such that when the legs 15 of the connecting member 80 are located therein and the toe portions engaged in the reduced portion 12 of the rod 11, the rod and attaching member will move in unison after the initial relative movement 85 which will occur because of the space which exists between the upper edges of the toe portions 16 and the cam face 14. The piston 10 is provided with an aperture through which fluid contained within the cylinder 4 may pass from one side to the other, thus 90 when the connecting element is disengaged from the rod 11 of the piston, the anchor will be free to move away from the mine. In order that the sounding ball may be released from the anchor prior to the disengagement 95 of the anchor from the mine, I have engaged the ring 19 of the ball with a pelican hook 20, which is pivoted at 21 to the anchor. The bill of this hook is engaged normally by the lower end of a slide 100 22, which moves through the keepers or guides 8. The upper end of this slide 22 extends at right angles to the body portion of the same, and is provided with a loop 23 which encircles the legs 15 of the connecting 105 member and rests upon projections 24 on said legs, so that upon the movement of the connecting member, the slide will be caused

to move. The loop 23 is preferably of such size that the legs of the connecting member may have movement laterally of the same.

With this construction it will be seen that 5 when the connecting member starts its movement within the socket 9, the slide 22 will immediately be moved upwardly so that the lower end of the same will be disengaged from the bill of the hook 20, and the hook 10 will be freed. This disengagement occurs before the connecting member is disengaged from the piston 11. Of course, upon the freeing of the hook 20, the sounding ball will 15 be released and will fall to its operative position. As this movement of the sounding ball occurs before the disengagement of the mine from the anchor, the sounding ball will have ample time to assume its operative position.

20 Referring to the modification illustrated in Figs. 5 to 7 inclusive, I have shown the anchor 1', the mine 2', and a sounding ball 3'. This sounding ball is preferably of the form illustrated in the drawing, being provided 25 with fins 4' which cause the ball to descend vertically through the water. This ball is further provided with a chamber 5' which is open at its upper end and in which the desired length of chain 6' is disposed, one end 30 of the chain being secured to a hook 7' in the chamber, and the other end to the anchor, in the usual manner. This chain passes upwardly through a notch 8' in the upper edge of the sounding ball. The 35 links of the chain are so disposed that it will be possible for the chain to draw through the notch. A cover 9' is detachably engaged with the upper end of the sounding ball and is preferably of such material that when disengaged therefrom it will sink. Thus, it 40 will be seen that when the sounding ball is disengaged from the mine, its downward movement will be vertical, and the chain will be automatically disengaged from the notch 45 8', which chain will at the same time move the cover 9' from the sounding ball.

This sounding ball is supported in the anchor by an arm 10', having a knob-shaped end 11', which extends through an opening 50 12' in the side of the ball. The relative size of this end of the arm and the opening 12' is such that, upon a swinging movement of the ball, it may disengage itself from the arm.

55 In order that this swinging movement of the ball may be prevented until after the mine has sunk to a predetermined depth, I have provided the following mechanism. The means for attaching the mine and anchor together, which is similar to that described in connection with Fig. 1, and includes a socket 13' and a connecting element 14', is provided. A slide 15', which moves 60 preferably in keepers or guides 16' formed 65 on a plate 17', which latter is secured to

the anchor, is engaged at its upper end with the connecting element 14' by a loop 18', in a manner similar to that described in connection with Fig. 1. The lower end of this slide passes through registering openings in 70 a strap 19' which encircles the lower end of the sounding ball, as illustrated. The lower end of this slide also passes through openings which register with the aforementioned openings and which are formed in ears 20', 75 permanently carried by the anchor 1.

Thus it will be seen that when the mine sinks to a predetermined depth, the movement of the connecting element 14' will commence. This will disengage the slide 15' 80 from the strap 19' so that the lower end of the sounding ball will be free to swing. The swinging movement of the sounding ball will disengage the same from the arm 10' so that the sounding ball may drop to its operative 85 position. The anchor will then be disengaged from the mine, in the manner which has been previously described.

What I claim is:—

1. The combination with a submarine 90 mine, its anchor and its sounding ball, of means for detachably securing the mine and anchor together and means for detachably securing the sounding ball to the anchor, the last mentioned means being controlled by the 95 first mentioned means.

2. The combination with a submarine mine, its anchor and its sounding ball, of means for detachably securing the mine and anchor together and means for detachably 100 securing the sounding ball to the anchor, the last mentioned means being controlled by the first mentioned means, and permitted by said first mentioned means to release the sounding ball prior to the release of the anchor. 105

3. The combination with a submarine mine, its anchor and its sounding ball, of means for securing the mine to the anchor including a connection which is capable of being rendered inoperative to hold the mine 110 and anchor together when the former has sunk to a predetermined depth and means, controlled by the aforementioned means, for detachably securing the sounding ball to the anchor. 115

4. The combination with a submarine mine, its anchor and its sounding ball, of means for securing the mine to the anchor including a connection which is capable of being rendered inoperative to hold the mine 12 and anchor together when the former has sunk to a predetermined depth and means, controlled by the aforementioned means, for detachably securing the sounding ball to the anchor, said first mentioned means being constructed to permit the release of the sounding ball prior to the release of the anchor. 125

5. The combination with a submarine mine, its anchor and its sounding ball, of means for securing the mine and anchor to- 13

gether including an element secured to the anchor and an element attached to the mine and to the first mentioned element and disengageable from the latter, said elements 5 having relative movement, caused by the buoyancy of the mine, prior to the disengagement of the latter from the former, and means for attaching the sounding ball to the anchor, which means is controlled by the 10 first mentioned means and is rendered inoperative upon the initial relative movement between the elements of the first mentioned means.

6. The combination with a submarine 15 mine, and its anchor, of means for securing the mine and anchor together including an element secured to the anchor and an element attached to the mine and to the first mentioned element and disengageable from 20 the latter, said elements having relative movement, caused by the buoyancy of the mine, prior to the disengagement of the latter from the former, and means for preventing such relative movement prior to the 25 launching of the mine.

7. The combination with a submarine mine, its anchor and its sounding ball, of means including a pair of separable elements for securing the mine and anchor together, 30 means for detachably securing the sounding ball to the anchor and a connection between said first mentioned means and said last mentioned means operable to permit the release of the ball upon the initial movement 35 of one of said separable elements of the first mentioned means.

8. The combination with a submarine 40 mine, its anchor and its sounding ball, of means including a pair of separable elements for securing the mine and anchor together, an element for detachably securing the sounding ball to the anchor and a connection between one of said separable elements and said last mentioned element for 45 rendering the latter inoperative upon the movement of the former.

9. The combination with a submarine

mine, its anchor and its sounding ball, of means including a pair of separable elements for securing the mine and anchor together, 50 which elements have appreciable movement before their separation, means for detachably securing the sounding ball to the anchor and a connection between one of said separable elements and the ball securing means for 55 rendering the latter inoperative upon the initial movement of the former and before the separation of said separable elements occurs.

10. The combination with a submarine 60 mine, its anchor and its sounding ball, of a pair of separable elements for securing the mine and anchor together, a pivoted hook mounted on the anchor and arranged to support the sounding ball, a slide connected to 65 one of said separable elements and engaged with the bill of the hook to prevent the disengagement of the sounding ball from said hook prior to the relative movement of the separable elements but permitting said disengagement upon the initial relative movement of said separable elements.

11. The combination with a submarine 70 mine, its anchor and its sounding ball, of means, independent of the cable drum, for 75 detachably securing the mine and anchor together, and means for detachably securing the sounding ball to the anchor, both of said means being connected together in such manner that the sounding ball will be released 80 from the anchor prior to the release of the anchor from the mine.

12. The combination with a submarine 85 mine, its anchor and its sounding ball, of means, independent of the cable drum, for detachably securing the mine and anchor together, and means for detachably securing the sounding ball to the anchor, both of said means being connected together in such manner that upon the release of one of said 90 means the other means will be released.

In testimony whereof I affix my signature.

JAMES HUBER.
